UNITED STATES PATENT OFFICE.

JOSEPH G. SWALLOW, OF NEW YORK, N. Y.

ELECTRIC POCKET-LAMP.

1,124,075.

Specification of Letters Patent. Patented Jan. 5, 1915.

Application filed September 4, 1913. Serial No. 788,126.

To all whom it may concern:

Be it known that I, JOSEPH G. SWALLOW, a citizen of the United States of America, and residing in the city of New York, in the county and State of New York, have invented a certain new and Improved Electric Pocket-Lamp, of which the following is a specification.

My invention relates to electric pocket lamps and the object of my invention is to provide a device of this character which is simple, economical and efficient in construction and by which a novel control of the direction of the light and of the lamp circuit is secured.

In the accompanying drawings, Figure 1 is a broken side elevation of a pocket lamp of one type in which my invention is embodied in illustrative manner; Fig. 2 is a similar view, at right angles, of the upper portion of the casing showing the bull's eye in a different position; and Fig. 3 is a plan of the lamp with the bull's eye open.

The invention is here shown applied to a pocket lamp of well known generally cylindrical character comprising a casing 10 of insulating material within which a battery 11 is placed. The opposite poles of the battery 12 and 13 are arranged at opposite ends of the battery cylinder, and contact with pole 13 is made at the lower end of the battery by means of the coil spring 14 carried by the screw cap 15 threaded on a collar 16 at the lower end of the casing 10. The current from this pole of the battery is led through straps 17 and 18, one of which is permanently connected to the collar 16 on the casing, while the other is carried above the upper end of the battery and bent down wardly to form a terminal 19. Between the adjacent ends of the strap 17 and 18 the usual switch 20 is arranged by which the circuit may be broken between the pole 13 and the contact 19. Cooperating with and normally in contact with the terminal 19, I provide a spring strap 21 fastened to the lamp casing at 22 from which point a flexible connection 23 leads to the center contact 24 of the lamp. The pole 12 of the battery is pressed by the spring 14 into permanent contact with the strap 25, the upper end of which is mechanically and electrically connected with the hinge 26, by means of which the lamp carrier 27 is mounted on the casing. The electrical connection to the side contact of the lamp is made through this

ring 27 in well understood manner and is consequently not explained in detail. The position of the center contact 24 of the lamp with relation to the spring strap 21, is such that upon the swinging of the lamp into alinement with the axis of the casing, the strap 21 is depressed out of contact with the terminal 19, thus interrupting the circuit. As soon however as the lamp is swung on the hinge 26 into angular position, the spring arm 21 rises into contact with the terminal 19, thereby completing the circuit through the lamp. The hinge elements at 26 may be fitted with sufficient friction to hold the lamp in any angular position to which it may be adjusted. The latch 28 engages within and holds the lamp ring in closed position in alinement with the casing. The switch 20 is thus merely an auxiliary and is normally left in the "on" position, since the lamp circuit is broken by the return of the lamp to alined position, which is the position of non-use for the device for the purposes for which it is particularly designed.

The lamp will be found particularly useful for meter readers who must take their readings generally in unlighted cellars and make entries upon their meter books at once upon the taking of the reading. The lamp is particularly serviceable for this purpose, since it may be dropped into the outside breast pocket of the coat, in which position the light is thrown down upon the book while the operator's hands are both left free for holding the book and making the entry therein. At the same time the pencil is returned to the pocket, the lamp may be turned over on its hinge into "off" position, so that the battery current is conserved.

The construction shown is but a single embodiment of my invention and merely exemplifies the latter. Various other constructions will readily suggest themselves, and I do not limit myself to the details shown:

I claim as my invention:—

1. An electric pocket lamp comprising a casing, a lamp carrier pivoted thereto, self-closing spring contacts in the lamp circuit and engaging means on the pivoted lamp carrier serving to open said contacts in a predetermined position of said carrier.

2. An electric pocket lamp comprising a casing, a lamp carrier pivoted thereto, self-

closing spring contacts in the lamp circuit and engaging means on the pivoted lamp carrier serving to open said contacts in the axial position of said carrier on the lamp 5 casing.

3. An electric pocket lamp comprising a casing, a lamp carrier pivoted thereto, a battery within the casing, a connection between one pole of the battery and one pole of the 10 lamp carrier, and a switch controlled connection to the other pole of the lamp carrier, said switch controlled connection comprising a pair of self-closing spring contacts, and means on the lamp carrier for automatically opening said switch on the 15 movement of the lamp carrier into predetermined position.

4. In an electric pocket lamp, a casing, a lamp carrier pivoted thereon and normally 20 aligned with the casing, a battery in the casing, circuit connections therefor through the lamp, said circuit comprising a pair of self-closing spring contacts and a bearing member on said lamp carrier serving to open 25 said contacts when said carrier is in its normal position, but moving out of engagement with said contacts to permit the same to close when said carrier is moved into angular position, substantially as described.

30 5. An electric pocket lamp comprising a casing, a lamp carrier pivoted thereto, spring contacts in the lamp circuit automatically closing to complete the lamp circuit in the open position of the lamp carrier and engaging means on the carrier serving to open said contacts and break the lamp circuit when the carrier is in closed position on said casing.

40 6. An electric pocket lamp, having a casing, a bull's eye pivotally mounted with relation thereto, a lamp carried by said bull's eye, spring contacts in the lamp circuit constantly tending to move into closed position and means for separating said contacts 45 in the closed position of said bull's eye and for freeing said contacts during the initial opening movement of said bull's eye whereby the lamp circuit is maintained through the major portion of the arc of travel of 50 said bull's eye in its open position.

7. An electric pocket lamp comprising a casing, a lamp carrier pivotally mounted thereon, a flexible conductor in one branch of the lamp circuit and moving with the

lamp carrier as the latter is swung in its 55 pivot, spring contacts in the lamp circuit, and means for opening the circuit at said contacts only in the closed position of the lamp carrier.

8. An electric pocket lamp comprising a 60 casing, a lamp carrier pivotally mounted thereon and having an open and closed position with relation thereto, spring contacts in the lamp circuit open in the closed position of the lamp carrier but automatically 65 closing to complete the lamp circuit on the movement of the lamp carrier into open position, said carrier having a substantial arc of movement while the contacts are in closed position, substantially as described. 70

9. An electric pocket lamp comprising a casing, a lamp carrier pivotally mounted thereon, spring contact in the lamp circuit constantly tending to move into closed position, contact engaging means on the lamp 75 carrier parting said contact on the closed position of the carrier but freeing the same during the initial portion of its movement into open position, whereby said contacts are freed and move into closed position for the 80 major portion of the arc of movement of said carrier, substantially as described.

10. An electric pocket lamp having a battery casing, a bull's eye pivotally mounted thereon, a lamp carried by said bull's eye, 85 a constant electrical connection to one terminal of the lamp through the battery casing, a switch in the connection to the other lamp terminal, said switch comprising spring contacts constantly tending to move 90 into closed position, means for separating said contacts in the closed position of the bull's eye and for freeing said contacts during the initial opening movement of said 95 bull's eye whereby the lamp circuit is maintained through the major portion of the arc of travel of said bull's eye in its open position, together with a flexible connection between one of said switch terminals and the coöperating lamp contact, for the purpose 100 described.

In testimony whereof I have signed my name to this specification, in the presence of two subscribing witnesses.

JOSEPH G. SWALLOW.
